UNITED STATES PATENT OFFICE.

WILLIAM P. PATTON, OF HARRISBURG, PENNSYLVANIA, ASSIGNOR OF THREE-FOURTHS TO WILLIAM T. HILDRUP, SR., WILLIAM T. HILDRUP, JR., AND JOHN HERVEY PATTON, OF SAME PLACE, AND SEYMOUR W. TULLOCK, OF WASHINGTON, DISTRICT OF COLUMBIA.

CAR-HEATER.

SPECIFICATION forming part of Letters Patent No. 368,488, dated August 16, 1887.

Application filed March 24, 1887. Serial No. 232,212. (No model.)

To all whom it may concern:

Be it known that I, WILLIAM P. PATTON, of Harrisburg, in the county of Dauphin and State of Pennsylvania, have invented certain new and useful Improvements in Car-Heaters; and I do hereby declare the following to be a full, clear, and exact description of the invention, such as will enable others skilled in the art to which it appertains to make and use of the same.

My invention relates to an improvement in car-heaters, and more particularly to a heater that is suspended beneath the body of a railroad-car to warm the interior. The primary object of my present invention is to provide a car-heating device that will generate gaseous fuel from hot water and hydrocarbon oil, ranging in specific gravity from 27° to 75°, hydrometer gage, to produce a fixed gas that is generated in volume in a close retort and supplied as it is required for consumption, the heat evolved by combustion of the fuel being utilized to raise the temperature of water in a proper heater, the water being distributed in tubular coils that are located in a car, the circulation of the heated water or low-pressure steam warming the car by radiation, the construction of the apparatus being such that the process of gas-generation and consequent combustion of same will be instantly arrested in case a car is thrown from the track and falls upon either of its sides.

A further object is to provide a car-heating device that may be located beneath the car by suspension and be supplied with materials from which to generate gaseous fuel from non-explosive oil or water in proper volume, the fuel being also an illuminant, that may be employed to light the car as well as heat it.

A further object is to so construct a car-heating apparatus, which is supported beneath a car, that convenient tanks for the supply of fuel-generating materials may be combined with the same and both the tanks and the water-heating chamber be compactly and securely sustained in position to operate properly while the car is in motion.

A further object is to provide a means

whereby the feeding of water from a supply-water tank to the water-heater will be self-regulating and be effected when the generation of steam creates a pressure in the heating-chamber above a fixed degree.

A further object is to provide a means whereby the feeding of water and carbonaceous material from which the gaseous fuel is generated may be regulated from the interior of the car.

A further object is to construct the water and carbon liquid supply tanks of a depending car-heater that they may be compactly located to feed the liquids to the heating apparatus by gravity, and that this feeding action may be controlled from the interior of the car.

With these ends in view my invention consists in certain features of construction and combination of parts that will be hereinafter specifically described, and pointed out in the claims.

Referring to the drawings making a part of this specification, Figure 1 is a side elevation in section of the water-heater in position beneath a car. Fig. 2 is a front elevation of the water-heating apparatus with the end removed to show interior mechanism. Fig. 3 is a front end elevation of the water-heater, showing its exterior. Fig. 4 is a cross-section of the device on a line, *x x*, Fig. 1. Fig. 5 is a side elevation of the device showing the water-regulating mechanism. Fig. 6 is a side elevation of the water-heater and tanks, showing oil-feeding device in position on side of heater opposite to the water-regulating mechanism. Fig. 7 is a plan view of the heater with the top plate removed. Fig. 8 is a plan view of the heating-coils in a car. Figs. 9 and 10 show side and front views of the oil-feeding automatic shut-off valve respectively. Fig. 11 is an elevation in section of the feed-water regulator. Fig. 12 is a sectional elevation of the gas generating and consuming mechanism.

A represents the outer shell of the water-heater. This is made of plate-iron, and is of suitable width and length to receive the water-

chambers A' A². The upper chamber, A', is made of plate-iron to neatly fit the rectangular shell A. It is of comparatively shallow depth, and is stayed by the rigid insertion of 5 the stay-bolts a a, &c., into the top and lower plates. The chamber A² is of the same width as the upper chamber, A', and somewhat shorter than it to afford room for a combustion-chamber, A³, in front of it.

10 Between the chambers A' and A² a space, b, intervenes. This is afforded by the insertion into the adjacent sheets of the threaded nipples c c, that are re-enforced by jam-nuts c', which have bearing contact upon each sheet, the 15 nipples affording water-passages between these chambers.

The lower chamber, A², is provided with a number of regularly-spaced flues d d, that extend between and into the upper and lower 20 sides, and are secured in the same rigidly to produce water-tight joints. A space, d', for heat circulation is made between the lower surface of the shell A and the lower side of the chamber A², the connected chambers A' A² 25 being supported upon the brackets d', at each end of the same, a vertical wall, e, that is erected at the front end of the chambers, aiding to retain them in this position.

A safety-valve, B⁵, is attached to the sides 30 of the upper chamber, A'. This is secured by a bracket, B⁶, which is bolted to the shell A, and is adapted to receive a spiral spring, e¹, that is of such relative proportion in diameter of the body of its coil as to afford a tensional strength sufficient to hold the valve e³ 35 in proper closed engagement with its seat until an objectionable pressure is developed in the water-heating chambers A' A², when it will rise and relieve this excess of pressure.

40 The gas generator and consumer C is located in the combustion-chamber A³. It consists of a metallic retort, D, of a proper size, preferably rectangular in form, to which is attached the gas-conducting pipes f, that lead 45 the gas as it is evolved in the retort to the burners g, which are adapted to mix air with the current of hydrocarbon gas, and by reason of the oxygen thus combined cause a smokeless combustion of the gaseous fuel.

50 In Fig. 12 the interior construction of the gas generating and consuming device is shown enlarged. The retort D is made, preferably, as shown, and has the pipes f f attached to its sides and ends. These pipes have diminished 55 gas-passages formed at the points 3 3, that inject gas generated in the retort into the burners g g, &c., which are perforated on their top surfaces to permit a combustion of the mixed gas and hot air. The upright pipes f f are 60 perforated at opposite points, f', above the jet-orifices 3 3, to admit atmospheric air to mix with the gaseous product evolved by heating the retort and injecting water and carbonaceous liquid in graduated quantity into this hot 65 retort. A similar burner, h, is secured to the pipes f at a point below the retort D. It is of sufficient size to heat the retort and generate

hydrocarbon gas therein in volume when the proper materials are introduced. The oil or other carbonaceous liquid is fed into the retort D by a pipe, L, which connects the retort with an oil-tank, S', located above it. The valve P' is so connected with the pipe L that the supply of oil fed into the retort may be regulated by the hand-wheel m from the outside of the car, and also by a similar wheel, m², located within the car, this wheel or handle being secured to the vertical rod m', which is an extension of the stem of the valve P' above the wheel m.

80 A means of cutting off the oil-supply from the retort D, when an accident derails the car and throws it over on one of its sides, is shown at R. (See Figs. 2 and 8.) This valve is made to close on its seat by the spring o. 85 It is held open by the yoke o', which is connected to the valve-stem o² of the valve, and is made to rest upon the toe of the swinging weight p, that retains it in a raised position with the attached valve r when the car is in 90 normal position on the track. When the car is made to assume a position exceeding forty-five degrees of inclination from a perpendicular line, or is thrown over on its side from accidental causes while in motion, the action of 95 gravity will swing the pendent weight p and cause it to disengage its toe s from the yoke o', releasing the latter and permitting the spring-actuated valve o to close instantly. The closure of the valve R will at once cut off 100 the supply of oil, and in consequence the flame in the combustion-chamber A³ will be extinguished upon the derailment of a car that upsets the same, or a collision that crushes it, thus obviating danger from fire.

105 Free access to the combustion-chamber A³ is afforded by the door E. A grate, i, is provided to hold materials to start a light fire, which is necessary to heat the retort when the heating apparatus is to be put into operation.

I preferably locate this heating device about the center of the car, below the body, and suspend it by looped bars I, which secure the shell A in suspended position to the truss-rods H of the car.

110 The combined water and oil tanks (shown in Figs. 7 and 10) are supported upon the truss-rods H of the car, and are secured to these rods by any suitable method. In order to make these devices compact and render the 115 transportation of the carbonaceous liquid safe from fire, I prefer to construct the oil or benzine tank inside the water-tank, and thus envelop the former-named receptacle with water when in use. The pipe L, which conducts the oil 120 from the tank S' to the retort D, is inserted through the wall of the water-tank S, a water-tight joint being secured by any proper method.

125 The water and oil tanks are each provided with a stop-cock, H', at one end to permit the filling of these tanks expeditiously at a station, and I prefer to make the tanks of such a capacity that a supply sufficient to last for

twenty-four hours' use of the heater will be held by them.

It is essential that water from the tank S be fed at proper intervals to the water-heating chambers A' A², and to accomplish this from the interior of the car the connecting-pipe W' is attached to the lower portion of the water-chamber A² and water-tank S, upon one side of the same, this pipe having a valve, W, introduced in its line to graduate the flow of water into the chamber A² by use of the vertical rod w and its handle.

In case of neglect to feed water at a proper time, and the heat evaporation, together with the use of water to generate gas, reduces the quantity of water in the chamber A', an automatic valve will open when the pressure rises above a proper degree in the chambers A' A². An enlarged view of this device is shown in Fig. 11, which will now be described.

The cylindrical valve U is constructed having a removable cap, w, on its upper end, a stuffing-box, y, on its lower end, and an inlet branch pipe, u², upon its side, the latter having a flange, w², to connect the chamber U to the side of the water-tank S. The interior of the chamber U is made cylindrically true, and is fitted with a spring plunger-valve, u, that is of sufficient length to cover the opening u² of the branch pipe where it intersects the chamber. An outlet, u', is made in the chamber U below the inlet branch u², a pipe, x, of proper size, being secured to the outlet-orifice to conduct water to the upper heating-chamber when the valve u is made to slide upward and uncover the inlet-opening u².

A rod, w⁴, extends downward to enter the flattened spherical chamber K. This is constructed of two dished and flanged portions that mate each other in diametrical size and concavity of interior surface. The flanges z z' are perforated to be screw-bolted together, and have a thin diaphragm, n, preferably made of metal, interposed between them before they are connected.

Upon the top surface of the diaphragm n a spiral spring, n', is seated to have bearing contact with the inner surface of the chamber K, this spring being made of proper tension to hold the valve u over the inlet-pipe opening and prevent an influx of water when pressure in the upper chamber, A', does not go above a predetermined degree. Upon the bottom of the chamber K the pipe N is attached. This extends through an opening in the side of the combustion-chamber A³, thence upward to penetrate the lower sheet of the chamber A' and enter this chamber. A branch pipe, v, is connected to the upright part of pipe N, and extends to enter the retort D at v', this branch v serving to supply the necessary feed-water for gas-generation.

It is evident that when a higher pressure is attained in the chamber A' than is desirable, due to want of water-supply and consequent free generation of steam, the diaphragm n and attached valve u will be raised sufficiently to

allow water to enter the chamber U, and from thence passing through the opening in the ring-valve u fill the chamber and be forced through the pipe N into the heating-chamber A'. When sufficient water has entered the chamber A' to lower the temperature by condensation of steam, the diaphragm n and attached valve u will resume their normal position and cut off the water-feed.

It should be distinctly understood that the gas generated in the retort D is a fixed gas, and not a mere vapor of the lighter hydrocarbon liquids, such as gasoline. I prefer to use coal-oil of such a density as will not vaporize in the atmosphere without heat. This may range in specific gravity from 27° to 72°, or from heavy coal-oil to crude benzine, preference being given to oil of about 54°, hydrometer gage. The use of water is necessary to dissociate the oil and furnish oxygen and hydrogen in volume to combine with the carbon of the oil to evolve gas. The proportion of water may be as high as two volumes of water to one of carbon, and thus furnish a gaseous fuel of great heating power. The use of water cuts down the cost of gas-generation and affords a very economical gaseous fuel.

Two heat-distributing coils, A⁶, are placed each in a box, which is preferably made to extend from end to end of the car beneath the floor, with a register at each seat. This is optional, as the coils A⁶ may be placed at the sides of the car in boxes or recesses provided to receive them. The boxes in which the coils are placed may be lined with metal to reflect the heat, and the contact with the wood be protected by asbestos boards or felt cloth, to prevent charring. The coils are attached to the branch pipe Y in the upper chamber, A', and a similar pipe, Y', to return the cooled water to the lower chamber, A².

In some cases it may be preferred to use two water-heating appliances, they being supported in a line across the bottom of the car, as shown in Fig. 5. When two heaters are used, a heat-distributing coil is attached to each heater, one on each side of the car. A steam-gage may be connected to the heating-chambers A' to indicate when pressure is increased above a desirable point, and a spring safety-valve, B⁵, set to raise and relieve this excess of pressure, is attached upon the side of the chamber A' to have a proper connection with its interior, as previously stated.

In operation the valve P' is opened to permit oil to enter the retort D. After a light fire of wood or charcoal has been started a sufficient length of time to heat the retort, the carbon vapor thus produced will issue from the burner h and be ignited. Water is now introduced by opening valve v², (see Fig. 2,) that is located in the pipe v. This will be instantly vaporized, and having chemical affinity for the carbon atoms, will combine with them. The absorption of carbon by the oxygen of the vaporized water will effect a decomposition of the superheated steam and a recomposition

takes place, producing an oxyhydrocarbon gas.

A continuation of the operation just described will force gas in volume from the burners *g*. This will be ignited and burn with an intense heat, which, impinging upon the adjacent surface of the water-heating chamber *A'*, the heat developed by the burners *g* will extend rearward into the space *b*, thence downwardly through the flues *d* into the space *d'*, and from thence through the perforations *d*³ into the combustion-chamber *A*³. The nipples *c* affording communication-passages for water between the lower chamber, *A*², and upper chamber, *A'*, the cooler water in the lower chamber will rise as the hot water is made to enter the distributing-coils, and after parting with its heat by radiation is returned to the lower chamber, *A*². In this manner a constant circulation of the water is maintained.

In case steam is formed that does not exceed the maximum pressure allowed in the chambers, the heating of the car will as effectually be accomplished by the radiation of its contained heat from the distributing-coils into which it rises.

As the candle-power of the gas produced in the retort *D* may be made sufficiently high to be serviceable as an illuminant, an outlet, *J*, may be made in the wall of the retort to allow a proper gas-service pipe to be attached thereto, which pipe may be extended to proper points in the car to furnish gas to light the interior of the same. In case it is desired, there may be a branch conductor-pipe led to a proper point to supply gas to a gas-range for cooking purposes, the latter-named feature being particularly available in the cooking department of a dining-room car.

The novel gas-generating retort and its connected burner, which are employed in combination with other devices to produce this safety car-heater, I do not desire to claim, broadly, at this time, but reserve the right to make a subsequent application for a divisional patent on the device for generation of hydrocarbon gas and burners that are adapted to directly consume the gas as evolved, mixing the gas with atmospheric air in proper volume to afford an economical result as to consumption of carbonaceous liquid. I do not wish to vitiate my right to secure this device, *per se*, and therefore make no specific claims for its construction in this connection.

Having fully described my invention, what I claim as new, and desire to secure by Letters Patent, is—

1. In a depending car-heater, the combination, with an oblong water-chamber supported horizontally beneath a car-floor and a heat-distributing coil located in the car above it, of a retort, a water-feed pipe, an oil-supply pipe, and burners, the retort being adapted to generate water-gas and the burners to mix this gas with air and consume the aero-gaseous mixture to heat water in the chamber and

cause it to circulate in the coil, substantially as set forth.

2. In a car-heater, the combination, with a water-containing chamber supported below a car, a gas generating and consuming device, and a heat-distributing coil in the car, of a water-supply tank and an oil-supply tank, the oil-tank being placed inside the water-tank, both tanks being supported above the depending water-heating apparatus, substantially as set forth.

3. In a depending car-heater, the combination, with a water-containing chamber, a gas generating and consuming device, and a heat-distributing coil, of a water-tank, an oil-tank contained in the water-tank, and a pipe leading from the oil-tank to the generator device, having a valve that will automatically close when the car is thrown over on either side, substantially as set forth.

4. In a depending car-heater, the combination, with a water-holding chamber that is contained in a shell, and a combustion-chamber at one end of the water-chamber and shell, of a gas generating and consuming device, a heat-distributing coil, a water-tank, an oil-tank located in the water-tank, and an automatic valve to shut off the oil from the gas-generator when the car is thrown over on either side, substantially as set forth.

5. In a depending car-heater, the combination, with a water-holding chamber, a shell to contain this chamber, a combustion-chamber at one end of the water-chamber and shell, and a heat-distributing coil located above the water-holding chamber, of a retort, a water-feed pipe, an oil-supply pipe, and burners that are adapted to mix the gas evolved in the retort with atmospheric air and consume it, substantially as set forth.

6. In a car-heater that is located beneath a car, the combination, with a water-holding chamber, a gas generating and consuming device, and a heat-distributing coil, of a water-tank and an oil tank, the oil-tank inside the water-tank, and an automatic water-feeding device that will open to admit water to the water-heating chamber when the temperature of contained water in this chamber rises above a predetermined degree, substantially as set forth.

7. In a depending car-heater, the combination, with a water-chamber located in a shell below a car-body, a combustion-chamber at one end of the shell and water-chamber, and a heating-coil located in the car above the water-chamber, of a water-tank and an oil-tank, a retort, a feed-water pipe attached to the water-tank and retort, an oil-supply pipe connected to the oil-tank and retort, and a valve that automatically closes the passage in the oil-pipe when the car is thrown over upon either of its sides, substantially as set forth.

8. In a depending car-heater, the combination, with two rectangular water-chambers lying horizontal, parallel to each other, and

connected to afford water circulation and provide a heat-passage between them, of a series of heat-conveying tubes located vertically in the lower water-chamber, a shell or jacket to 5 inclose the water-chambers, a combustion-chamber at one end of the shell, and a gas-generator and burners located in the combustion-chamber, substantially as set forth.

9. In a depending car-heater, the combination, with a rectangular shell, two water-chambers located one above the other in this shell, a combustion-chamber at one end of the shell, and a heating-coil placed in the car, of a retort, a water-feeding pipe, an oil-supply 15 pipe, oil and water tanks supported below the car-floor, an automatic water-feeding device, and an automatic oil-cut-off valve that closes when the car is thrown over on either side, substantially as set forth.

10. In a car-heater, the combination, with a 20 shell, two water-chambers that are placed in shell, the one above the other, the lower water-chamber shorter than the upper water-chamber, and a combustion-chamber, of a gas-generating retort, burners to consume gas and 25 air, a water and oil tank located above the water-heater, and a hot-water-circulating coil placed in the car above the water-heater, substantially as set forth.

In testimony whereof I have signed this 30 specification in the presence of two subscribing witnesses.

WILLIAM P. PATTON.
